UNITED STATES PATENT OFFICE

2,581,346

DUST MOP CLEANER

Eugene Autry, Brooklyn, N. Y.

Application February 25, 1949, Serial No. 78,419

4 Claims. (Cl. 15—91)

1

This invention relates to a novel construction of cleaner or beater for dust mops which may be utilized indoors for beating dirt from a dust mop while disposed in an enclosed space to prevent the dust and dirt from returning to the atmosphere and including a receptacle portion into which the dust and dirt, removed from the mop head, is temporarily deposited and from which the dust and dirt can be readily emptied.

More particularly, it is an aim of the present invention to provide a beater-type dust mop cleaner including a resilient mop support for co-operation with a flexible beater which is adapted to be manually actuated to provide a combination which will effectively remove dust and dirt from a mop head.

Various other objects and advantages of the invention will hereinafter become more fully apparent from the following description of the drawings, illustrating a presently preferred embodiment of the invention, and wherein:

Figure 1 is a horizontal sectional view of the dust mop cleaner taken substantially along a plane as indicated by the line 1—1 of Figure 2;

Figure 2 is a vertical sectional view of the dust mop cleaner, with the beater thereof removed, taken substantially along a plane as indicated by the line 2—2 of Figure 1;

Figure 3 is a fragmentary side elevational view of a portion of the container of the invention;

Figure 4 is a diametrical sectional view partly in side elevation showing the cleaner with the beater applied and with a mop applied thereto with the mop head disposed to be cleaned by the beater;

Figure 5 is an end elevational view of the beater, looking toward the beater head, and

Figure 6 is a side elevational view thereof.

Referring more specifically to the drawings, the dust mop cleaner in its entirety and as illustrated in Figure 4 is designated generally 7 and includes a container, designated generally 8 composed of a bottom section, designated generally 9 and a top section, designated generally 10.

The container 8 is illustrated as being substantially cylindrical in shape in cross section but it will be readily apparent that this shape thereof is not critical and that the container could be rectangular or of various other shapes. The bottom section 9 has a substantially flat bottom wall 11 which is adapted to rest on any suitable supporting surface, not shown, for supporting the cleaner 7 and also includes a substantially cylindrical upwardly extending side wall 12 having an open top. The side wall 12 is provided with an in-

wardly bowed annular upper portion 13 and therebeneath and spaced therefrom is provided with an inwardly bowed portion forming an inwardly projecting annular rib 14. A plurality of lugs or brackets 15 are struck out from the internal rib portion 14 of the bottom container section 8 and extend inwardly therefrom and are each provided with an aperture 16, as seen in Figure 1, for a purpose which will hereinafter become apparent. The wall 12 above the annular rib 14 is provided with an upwardly opening notch 17 which opens outwardly of the upper edge thereof.

The upper container section 10 includes a cylindrical wall 18 defining the lower portion thereof of which is inwardly bowed at its lower end to provide an inwardly projecting annular bead 19 adapted to form a detachable snap fit engagement with the inwardly bowed upper portion 13 of the bottom section 9 for releasably retaining the upper section 10 thereon. Said upper section 10 is provided with an upwardly extending conical-shaped top portion 20 having an opening 21 at the apex thereof for receiving a sleeve 22 which is suitably secured therein and which is supported thereby substantially axially of the container 8.

The sleeve 22 provides a bushing for reciprocably receiving the lower enlarged portion 23 of an elongated handle having a restricted upper portion 24 which is normally disposed above the container 8. A beater head 25 is mounted on the lower end of the handle portion 23 and is clamped between collars 26. A headed fastening 27 extends centrally through the collars 26 and the head 25 and longitudinally into the lower end of the handle portion 23 for attaching the head 25 thereto and so that the handle is disposed substantially perpendicular to the plane of the head 25. The head 25 is illustrated as being substantially circular or disk-shaped but may be of any other desired shape and is provided with a plurality of openings 28. The head 25 may be formed of any suitable relatively thick material which is relatively flexible or resilient.

A spider-like mop head support, designated generally 29 is mounted in the upper portion of the bottom container section 9 and is normally disposed substantially parallel to the container bottom 11. The support 29 includes a ring 30 and a plurality of strap members 31 which are connected thereto and which project radially therefrom. Each of the strap members 31 has its ends turned back upon themselves and secured by a fastening 32 to provide a loop 33 at the inner end of each strap member 31 for engaging the ring 30 and a loop 34 at the opposite, outer

end of each strap member 31 which is engaged by a hook 35. Each hook 35 has a shank terminating in a downturned terminal 36 which engages through one of the openings 16 for detachably connecting one of said hooks 35 to each of the lugs or brackets 15 so that the spider-like support 29, comprising the ring 30, straps 31 and hooks 35 is detachably supported in the upper portion of the bottom container section 9 by the lugs or brackets 15, as clearly illustrated in Figure 1. Either the ring 30 or the straps 31 is of a resilient material or both the ring 30 and straps 31 may be resilient, if desired.

To employ the cleaner 7 for cleaning a mop, designated generally 37 and illustrated in Figure 4, the upper container section 10 with the beater is removed from the bottom container section so that the head 38 of the mop 37 can be positioned on the mop support 29 and with the mop handle 39 extending outwardly through the notch 17. The upper container section 10 is then re-applied and it will be apparent that it will close the upper end of the notch 17 to retain the mop head 38 in position on the support 29. The operator then grasps the handle portion 24 to impart an up and down reciprocating motion thereto to cause the beater head 25 to be reciprocated in the container 8 and vertically back and forth toward and away from the mop head 38, said beater head being guided by the sliding engagement of the handle portion 23 in the sleeve 22. The beater head 25 on each down stroke will strike the mop head 38 causing the support 29 to yield downwardly and as the beater head 25 is moved upwardly the support 29 will rebound in an upward direction carrying the mop head 38 with it. The flexibility or elasticity of the beater head 25 will cause it to be swung or slapped against the mop head 38 and if the beater head 25 is reciprocated rapidly, the mop head 38 will be struck as it is moving upwardly on the rebound of the support 29 so that dirt and dust will be readily beaten therefrom and deposited into the bottom portion of the container section 9 from where it can be readily emptied when the upper container section 10 and mop 37 are removed.

Various modifications and changes are contemplated and may obviously be resorted to, without departing from the spirit or scope of the invention as hereinafter defined by the appended claims.

I claim as my invention:

1. A dust mop cleaner comprising a container composed of top and bottom detachably connected sections, a resilient, spider-shaped mop head support mounted in the bottom container section, spaced from the container bottom and extending transversely of the container, a beater including an elongated handle extending reciprocably through the top of the container for reciprocating movement longitudinally of the container and toward and away from said support, said beater

5 including a head disposed at the lower end of the handle adapted to strike a mop head mounted on the support between the beater head and mop head support, said spider-shaped mop head support including a ring, a plurality of straps connected to and extending radially from said ring, and a hook connected to the outer end of each of said straps and to a portion of the container for detachably supporting the mop head support within the container.

2. A dust mop cleaner comprising a container composed of top and bottom detachably connected sections, a resilient, spider-shaped mop head support mounted in the bottom container section, spaced from the container bottom and extending transversely of the container, a beater including an elongated handle extending reciprocably through the top of the container for reciprocating movement longitudinally of the container and toward and away from said support, said beater including a head disposed at the lower end of the handle adapted to strike a mop head mounted on the support between the beater head and mop head support, said bottom section having an upper edge provided with a notch adapted to accommodate a handle of the mop head below the top container section.

3. A dust mop cleaner as in claim 1, said beater head comprising a limber disk-shaped member having a central portion secured to the handle.

4. A mop head cleaner comprising a container, a resilient spider-shaped member mounted in the container including a ring, a plurality of straps fixed to and projecting radially from the ring and means secured to the outer ends of the straps and connecting the straps to the container to normally support said spider-shaped member within the container and with the parts thereof in extended coplanar positions; a beater head disposed in the container between which and said spider-shaped member a mop head is adapted to be disposed, and actuating means connected to the beater head and projecting from the container and operable to forcibly displace the beater head toward the spider-shaped member.
